ELECTRICAL CAVITY RESONATOR

George L. Usselman, Port Jefferson, N. Y., assignor to Radio Corporation of America, a corporation of Delaware

Application November 16, 1943, Serial No. 510,495

3 Claims. (Cl. 178—44)

1

This invention relates generally to high frequency electrical resonators and, more particularly, to cavity resonators. The term "cavity resonator" is herein employed to designate a closed electrically conducting surface enclosing a hollow space, and wherein the enclosure contains a periodically repeating electromagnetic field.

Heretofore, in using cavity resonators, particularly rectangular shaped cavity resonators, it has been customary to change the length of the cavity in order to vary the frequency. When a certain minimum dimension is reached, however, the "width" becomes the length and a further change in the two moving walls does not change the frequency, or the action becomes unstable.

Among the objects of the present invention are: to provide a cavity resonator having improved tuning means for controlling the frequency of the resonator and which overcomes the foregoing difficulty; to provide a variable frequency cavity resonator having tuning means which simultaneously changes the effective dimensions of all walls of the resonator; to provide a cavity resonator equipped with tuning means which changes the volume of the resonator in substantially symmetrical manner around its central axis.

According to an embodiment of the invention, the cavity resonator is provided with tuning means composed of a plurality of curved vanes. These vanes surround the central axis of the resonator to form a closed wall and are hinged at the ends farthest removed from the central axis. The other ends of the vanes are in constant contact with the sides of the neighboring vanes in all tuning or operating positions, thus forming a closed symmetrical cavity at all times. A gear arrangement is employed to control the movement of all vanes simultaneously in unicontrol manner.

A more detailed description of the invention follows in conjunction with a drawing, wherein

Figure 1 is a partial sectional view of a cavity resonator equipped with tuning vanes in accordance with one embodiment of the invention. This view shows the resonator from one end, with the end wall removed.

Figure 2 is a schematic diagram of a pair of cavity resonators having generally the structure of Figure 1, arranged in an ultra frequency oscillation generator circuit; and

Figure 3 is a detail of the structure of Figures 1 and 2 and shows the manner in which the vanes contact the top and bottom walls of the resonator.

2

Referring to Figure 1 in more detail, there is shown the top or bottom view of a cavity resonator of the pancake type, with one end wall removed. The central axis of this cavity resonator is indicated at 10. The invention resides primarily in the use of a multiplicity of curved metallic vanes V1, V2, V3 . . . V6, so arranged symmetrically around the central axis 10 that they can be simultaneously moved to enclose more or less volume of the resonator, and thus vary the frequency of the resonator. The vanes are each hinged at one end at A by means of hinged bolts which pass through the metallic end walls, P1, P2. One end wall is not shown in Figure 1 in order to show the interior of the cavity resonator while the other end wall is shown. The vanes V1 . . . V6, are keyed rigidly to the bolts and have bearings in the metallic end walls or plates P1, P2. At the end of each bolt A there is rigidly fastened an arm M. The ends of the arms M farthest removed from the bolts A engage a ring R by means of slot-shaped holes or prongs. Gear teeth are cut on a portion of ring R to engage a pinion gear G. The edges of the vanes V1 . . . V6 are provided with brushes or contact springs B to make good electrical contact with the end walls P1, P2 of the cavity resonator, as shown in more detail in Figure 3. These brushes may be of any satisfactory type which will allow free movement of the vanes and make good electrical contact with the plates against which they bear. The end walls P1, P2, are separated by spacers X and also by the bolts A which hold the plates P1, P2 rigidly in place. Spacers X may be made of insulating material or metal, although metal spacers are preferred because of their greater strength and the ease of machining to the correct dimension.

The vanes V1 . . . V6 are so curved and arranged that the ends of the vanes farthest removed from the bolts A are in constant contact with the sides of the neighboring vanes in all of the operating or tuning positions. These contact ends are preferably provided with suitable brushes that make good electrical contact against the sides of the neighboring vanes. In this way the vanes always form a closed symmetrical cavity at all times. This is made possible by the fact that there are employed six vanes which comprise inverted segments on the circle on which they are hinged. These six vanes are uncontrolled by the gear G and operate to reduce the cavity volume to an extremely small space when it is desired that the cavity resonator have minimum volume and the highest frequency position.

The dot and dash lines in Figure 1 indicate the position of the vanes in the maximum volume and lowest frequency position. The position of the vanes shown in Figure 1 is merely given by way of illustration and shows the vanes arranged in an intermediate frequency position between the lowest and highest frequencies of the tuning range.

In operating the cavity resonator of Figure 1, let us assume that it is desired to increase the 10 frequency of the resonator. To do this, the volume of the cavity must be decreased. To achieve this, the gear G should be turned clockwise. The movement of the gear G in a clockwise direction will turn the ring R in a counter-clockwise direction and the latter, in turn, will act on the arms M and hinges A to swing the vanes toward the center of the cavity, thus reducing the volume of the cavity of the resonator, as desired. Because the ends of the vanes farthest removed from the hinges A are always in contact with the sides of the neighboring vanes in all of the operating or tuning positions, there will always be formed a closed symmetrical cavity around the central axis 10 of the cavity resonator.

Although only six vanes have been shown in the resonator of Figure 1, it should be understood that the invention is not limited to this number since the vanes may have shapes different from that illustrated and may be composed of a number of vanes different from six.

Figure 2 illustrates, by way of example only, a schematic diagram of an ultra high frequency generator employing a pair of cavity resonators constructed in accordance with the principles of Figure 1, in conjunction with a vacuum tube T. The pair of cavity resonators of Figure 2 are designated generally by the numerals 20 and 21 and comprise a circular plate having a top wall P1 and a bottom wall P3 and a common or intermediate wall P2. The hinged bolts A passing through all three flat metallic plates P1, P2 and P3 rigidly maintain these plates in position. The common wall P2 is provided with an aperture at its center to accommodate the vacuum tube T. The grid of the tube is capacitively coupled to the wall P2 by means of a metallic flange 2 which is separated from the wall P2 by mica insulation 3. Similarly, the anode of the tube T is capacitively coupled to the end wall P1 by means of a metallic flange which is separated from the wall P1 by means of a mica spacer 3'. The capacities between the anode and plate P1 and between the grid and plate P2 are of extremely low impedance to energy of the operating frequency, thus constituting by-pass condensers. Positive polarizing potential for the anode is supplied over lead 6 which passes through an aperture in the end wall P1 to connect with the anode flange. Bias for the grid is supplied over lead 7 which is connected to the grid flange 2. This lead 7 is preferably taken out through a hole drilled radially in the plate P2. Although not shown in the drawing, the bias for the grid is obtained from a grid-leak resistor in the conventional manner. The cathode of the tube T is directly connected to the bottom plate P3. The cathode heater leads H are brought out directly from the plate P3 through an aperture. Each of the cavity resonators 20 and 21 are provided with the six vanes of Figure 1 in substantially the same manner shown in Figure 1. Only two vanes, V1 and V4, are shown for the upper cavity resonator 20 and two vanes V1', V4', are shown for the lower cavity

resonator 21. The vanes, which are correspondingly designated, except for the prime designations, are located in the same straight line one above the other and move simultaneously with each other. In order to change the tuning of the cavity resonator there is shown the gear G controlled by means of a knob N fastened to the shaft thereof. To obtain feedback between the cavity resonators 20 and 21 there are provided a pair of conducting loops 4 and 5 in the interior of the resonators. These conducting loops pass through apertures in the plates P1 and P3 and connect with a parallel conductor or Lecher wire circuit W1, W2. This Lecher wire circuit is provided with a short-circuiting bar F which is adjustable or movable over the lengths of the parallel conductors W1, W2. For tuning the cavity resonators, it is only necessary to turn knob N which will rotate pinion gear G in engagement with ring R. Movement of ring R will cause simultaneous movement of all the vanes within the two cavity resonators through the action of arms M linked to the ring R at one end and linked to the vanes at the other. Turning the gear G in a clockwise direction will decrease the volume of the two cavity resonators 20 and 21 and increase the frequency of the oscillator, while movement of the gear G in a counter-clockwise direction will increase the volume of the cavities enclosed by the vanes and decrease the frequency of the oscillator.

In a construction of the resonators of the invention, it is preferred that the end walls and the movable elements forming the side walls be made of copper or some other equally good conducting material. The cavity resonators may, however, be made of any material and its surfaces coated with copper, silver or gold.

What is claimed is:

1. A cavity resonator having flat stationary end walls, and movable side walls in the form of a plurality of movable vanes symmetrically arranged around and surrounding the central axis of said resonator, one end of each vane being pivoted with respect to an axis which is stationary relative to said end walls while the other end of each vane is adapted to engage an adjacent vane at a point intermediate the ends of the adjacent vane.
2. A cavity resonator having stationary top and bottom walls and movable side walls of high conducting material, said side walls comprising a plurality of metallic vanes arranged symmetrically around the central axis of said resonators and in slidable contact at their top and bottom side edges with said top and bottom walls, respectively, said vanes being hinged at their outer edges and in adjustable contact with adjacent vanes solely at their inner edges, and rotatable means linked to said vanes for moving said vanes simultaneously to thereby change the effective volume of said resonator, said last means including a circular gear which is larger than the effective area of and coaxially arranged with respect to said cavity resonator and located adjacent the outer edges of said vanes, said vanes being separately linked to said gear at their hinged edges.
3. A cavity resonator comprising stationary top and bottom walls and movable side walls, said side walls being composed of a plurality of vanes, means supporting the outer ends of said vanes between said top and bottom walls and in pivoted relation thereto, and revolvable means linked to said vane supporting means for imparting simul-

taneous movement to the other ends of said vanes to the same extent and in the same relative direction.
